STRIP GUIDE ATTACHMENT

Stanley J. Ketterer, St. Louis, Mo.

Application January 21, 1948, Serial No. 3,465

5 Claims. (Cl. 112—139)

1

The present invention pertains generally to an attachment for sewing machines, and more particularly to an improved attachment for sewing machines of the type used in the shoe and kindred leather goods industries.

Specifically, the invention consists of an improved attachment for such sewing machines which will facilitate the binding of raw or unfinished edges of leather in order to impart thereto a finished, ornamental appearance.

The present device is especially adapted for finishing the edges of vamps, quarters, or other portions of ladies' shoes and slippers, and enables an operator to perform such operations more quickly and accurately than is possible with binders in use today.

The attachment is so designed that it can be quickly installed on virtually all of the standard sewing machines of the type referred to, without any change whatever, in their present construction.

Therefore, the primary objects of the invention are to provide an attachment which requires no change in standard sewing machine constructions for its ready installation or removal, and which includes means for feeding the binding tape in a manner adapted to overcome the disadvantages of attachments now in use.

One of the disadvantages inherent in known binders is the absence of means for accommodating tapes the thickness of which varies to more than a perceptible degree.

The instant device provides means whereby binding tapes ranging from the minimum to a maximum thickness may pass therethrough without friction.

Another disadvantage inherent in known binders is the absence of means whereby tapes of different widths may be quickly and easily maintained in proper alignment while passing through the guide. A few of the binders now in use are equipped with such means, but these require the use of tools for adjustment, and also require considerable skill on the part of the operator.

The instant device is equipped with a pivoted manually operable lever having an arcuate edge which may be quickly and easily brought into contact with one edge of the binding strip for this purpose, and the operation of which requires neither tools nor skill.

Another advantage provided by the invention, and not found in conventional binders, resides in the arrangement whereby the tape guide is pivotally mounted about the presser roller stud, so that the former may be adjusted for binding op-

2

erations on leather goods or different weights without impairing its position relative the roller.

Further objects, advantages, and features of the invention will be apparent or particularly pointed out in the description to follow, reference being also had to the accompanying drawing in which the preferred form of the device is illustrated.

In the interest of clarity, all of the views are 10 portrayed on an enlarged scale, being approximately twice actual size.

In said drawing:

Fig. 1 is a perspective view of the attachment comprising the present invention;

Fig. 2 is an elevational view thereof, in a position approximate that which it occupies when installed on a standard sewing machine;

Fig. 3 is an elevational view of the device turned one hundred and eighty degrees from its Fig. 2 position;

Fig. 4 is a sectional view taken approximately on the line 4—4 of Fig. 2;

Fig. 5 is a similar view taken approximately on the line 5—5 of Fig. 1, some parts appearing 25 in the background being omitted;

Fig. 6 is a fragmentary elevational view of the upper portion of the device particularly illustrating portions not appearing in Fig. 1;

Fig. 7 is a perspective view of a pivoted manually operable lever included in the device;

Fig. 8 is a side elevational view of the device installed on a standard sewing machine, portions only of the latter being shown, and these more or less diagrammatically;

Fig. 9 is a vertical sectional view taken approximately on the line 9—9 of Fig. 8; and

Fig. 10 is a sectional view of a piece of leather or the like having a binding tape stitched thereto.

With particular reference to Figs. 1 through 5, 40 and Fig. 8, the binder of this invention is designated as a whole by the reference character 15.

It includes a tape or binding strip guide generally designated 18, a pivotally mounted, manually operable tape lining lever generally designated 20 which is shown per se in Fig. 7, and an angularly contoured supporting bracket generally designated by the reference character 22.

The guide 18 comprises a flattened tube, preferably of stainless steel, and includes opposed flat walls 24 and 25 merging into rounded end walls 26 and 27, as best seen in Fig. 1.

As shown especially in Fig. 5, there is provided at the upper end of said guide a relatively narrow tape-receiving opening or slot 29, adapted to accommodate binding tapes ranging from a mini-

imum thickness to a thickness approximately intermediate the maximum.

As also best seen in said view, the guide 18 is further provided with a relatively wider tape-receiving opening or slot 30, adapted to accommodate tapes ranging from an approximately intermediate thickness to a maximum thickness.

The lower or discharge end of the guide terminates in an arcuate portion 32 which serves as a common outlet for tapes which enter either of said inlet slots 29 or 30.

Both of said slots are coextensive transversely of the device, so that binder tapes of varying width may be inserted in either. To provide an entrance for the slot 30, the wall 25 is cut away as at 34 in such manner that the rounded end wall portion 26a remains intact, whereas from the cutaway portion there is fashioned an integral ear 36 which is then bent to lie in the plane of the wall 24.

Thus, as best seen in Figs. 1, 4, and 6, this ear projects laterally from and includes the adjacent portion of the end wall 27, and has a threaded aperture 37 to receive a pivot screw 38 by means of which the lever 20 is secured thereto.

The lever 20 includes a finger portion 40 which extends above the pivot 38, and a depending portion 42 provided with an integral lateral projection 43 of the configuration shown. There is a slot 44 formed in the wall 27 through which the projection 43 extends so as to lie within the arcuate discharge portion 32 of the guide, that is, between the walls 24 and 25 thereof.

As shown in the drawing, the contour of the projection 43 is so designed as to follow that of the arcuate guide portion 32, so that manipulations of the lever 20, such as that indicated by the broken lines of Fig. 4, may readily be had.

The projection 43 terminates in an arcuately contoured marginal edge portion 45, and an aperture 46 is provided approximately centrally of the lever 20 through which the pivot screw passes. It is here noted that said screw is drawn tight enough to frictionally maintain the lever 20 in a selected position, so that it is not necessary for the operator to use a screw driver or other tool either before, during, or after an adjustment.

A feature of the invention resides in the bracket 22 which supports the binder, and by means of which the device may be easily attached to standard sewing machines, as will appear.

The configuration of said bracket is readily apparent from an inspection particularly of Figs. 1, 3, and 5, where it is seen to include a body portion 48 and an integral substantially vertically disposed wall portion 49 preferably strengthened by an angular flange portion 50.

Included in said wall is a flat portion designated 52, which is provided with an aperture 53 of a size to accommodate the presser roll studs of standard sewing machines. The body portion 48 of the bracket is provided with an aperture 56, as shown in Fig. 5, and preferably, a threaded apertured boss 57 is welded or otherwise secured to the wall 24 of the guide member to receive a tap screw 58 by means of which said bracket is adjustably secured to the guide 18.

As best seen in Figs. 1 and 5, the wall 24 of the guide is recessed as at 60, and the wall 25 as at 62 to accommodate the presser roll of standard machines as will appear.

All of the elements included in the present invention have thus far been described, and are identified by reference characters in the drawing. A brief description of the manner in which

the binder is attached will now follow, it being understood that conventional sewing machine parts are more or less diagrammatically portrayed in Figs. 8 and 9.

The parts referred to include the following: a presser wheel 75, a presser wheel supporting stud 76, a reduced integral threaded extension 77, nut 78, washer 79, presser roller supporting arm 80, a threaded aperture 81 therein, a needle 82, a post or work support 83, and a feeder 84. The roller supporting arm is secured to the usual bracket carried by the vertically movable presser bar, as is understood. The post 83 extends upwardly from the base of the machine, also as understood.

To attach the binder quickly, it is merely necessary to align the opening 53 with the aperture 81, and then to pass the stud 76 successively through the roller 75, washer 79, and opening 53, with the threaded shank 77 engaging the aperture 81 and projecting beyond the arm 80 to receive the nut 78, as clearly shown in Fig. 9. Due to the bifurcated portion of the guide provided by the recesses 60 and 62, such mounting of the presser roller 75 is facilitated, and the latter is freely rotatable and adapted to contact the tape.

With the binder in place, slight transverse adjustments of the guide 15 relative the bracket 22 may be made by loosening the tap screw 58. After a length of relatively thin tape *x* from a suspended roll, not shown, has been fed through the inlet 29 and into engagement with the presser roller, the arcuate edge 45 of the projection 43 is brought into contact with the adjacent edge of said tape by manipulating the lever 20. A similar manipulation of said lever may follow the insertion of a length of relatively thick tape *y*.

It is not deemed necessary to explain a binding operation, since, in use, the present binder operates in the same manner as conventional binders. The result obtained is illustrated in Fig. 10, which portrays the binding strip *x* stitched to a piece of leather *z*, the stitching being adjacent the marginal edges of both the binding strip and the leather.

From the foregoing, it is manifest that the invention provides novel advantages not found in other binders. The preferred embodiment of the invention has been illustrated and described, but obviously it admits of modifications within the scope of the appended claims.

What is claimed is:

1. A strip guide attachment for standard sewing machines having a presser roller and its supporting stud and attachment arm, a needle and feed mechanism; said attachment including a guide member having separate inlets for the reception of binding strips of varying thicknesses, lever means pivotally mounted on a lateral extension integral with the guide member for engaging one edge of strips of varying widths which may pass through said guide member, an angularly contoured supporting bracket adjustably secured to the guide member, an aperture in the bracket to receive said presser roller supporting stud, and recesses provided in opposed walls of said guide member to accommodate the presser roller aforesaid.

2. In a strip guide attachment of the character described, adapted for use with a sewing machine having a presser roller and its supporting stud and attachment arm, a needle and feed mechanism; a pair of opposed flat walls merging into a pair of opposed arcuate walls to form a guide member of flattened tubular configuration,

a relatively narrow binding strip receiving portion and a relatively wide binding strip receiving portion provided therein, said strip receiving portions being coextensive transversely of the guide, an arcuately formed strip-discharging portion recessed to accommodate said presser roller, and an integral laterally projecting extension on the guide for pivotally supporting a manually operable lever having a projection adapted to be brought into engagement with one edge of a binding strip passing through said guide.

3. In a strip guide attachment of the character described, adapted for use with a sewing machine having a presser roller and its supporting stud and attachment arm, a needle and feed mechanism; a pair of opposed flat walls merging into a pair of opposed arcuate walls to form a guide member of flattened tubular configuration, a relatively narrow binding strip receiving portion and a relatively wide binding strip receiving portion provided therein, said strip receiving portions being coextensive transversely of the guide, an arcuately formed strip-discharging portion recessed to accommodate said presser roller, an integral laterally projecting extension on the guide for pivotally supporting a manually operable lever having a projection adapted to be brought into engagement with one edge of a binding strip passing through said guide, an elongated slot formed in one of said arcuate walls through which said projection extends, and a threadedly apertured boss on one of said flat walls to receive a fastening element by means of which a supporting bracket is secured to said guide.

4. In a strip guide attachment of the character described, adapted for use with a sewing machine having a presser roller and its supporting stud and attachment arm, a needle and feed mechanism; a flat tubular member through which binding strips of varying widths may pass, and means for maintaining one edge of such strips in contact with one end wall of said tubular member, said means comprising a manually shiftable lever pivotally mounted on a lateral support rigid with

said member, said lever including a finger portion above and a depending portion below its pivot, a lateral projection on the end of said depending portion extending through an opening provided in the other end wall of said tubular member, and an arcuate marginal edge on said projection adapted to be brought into contact with the other edge of such strips by manipulation of said lever.

10 5. In combination with a standard sewing machine having a presser roller and its supporting stud and attachment arm, a needle and feed mechanism; a binding strip guide supported on a bracket adapted for mounting on said attachment arm, said guide including a pair of strip receiving inlets and a single outlet, recesses formed in said guide to accommodate said presser roller, and manually operable means for maintaining binding strips passing through said guide 15 in proper alignment with said roller, said means including a lever mounted on a pivot screw, an ear portion integral with and extending laterally from said guide to receive the threaded portion of said pivot screw, an integral lateral projection 20 on the lower end of said lever, and a slot formed in one wall of the guide through which said projection extends so as to lie within the discharge portion of said guide for maintaining strips passing therethrough in proper alignment with said 25 roller.
